CLAIM

The ornamental design for an automobile body part—engine cover, as shown and described.

DESCRIPTION

FIG. 1 is a front view of an automobile body part—engine cover of our present design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a top, right perspective view thereof.

Portions of the engine cover shown in broken lines form no part of the claimed design.

1 Claim, 7 Drawing Sheets
